UNITED STATES PATENT OFFICE.

SALOMON VLESSING, OF LEEUWARDEN, NETHERLANDS.

DRIER FOR VEGETABLES.

1,320,721.

Specification of Letters Patent.

Patented Nov. 4, 1919.

Application filed March 8, 1918. Serial No. 221,301.

To all whom it may concern:

Be it known that I, SALOMON VLESSING, manufacturer, a subject of the Queen of the Netherlands, residing at Leeuwarden, Province of Friesland, in the Kingdom of the Netherlands, have invented certain new and useful Improvements in Driers for Vegetables, of which the following is a specification.

- 10 The invention relates to driers for vegetables and the like and consists in certain improvements thereof. In an apparatus of the kind there are drying chambers, in which are placed in several horizontal rows 15 above each other, a plurality of drying screens. These screens are all pivotally mounted on parallel spindles. The vegetables are placed on the screens, and are dried by a current of heated air, which is introduced at the bottom of the apparatus. The 20 vegetables, which are first heated and "bleached", are placed on the upper row of screens; the drying process being continued, the vegetables are brought to a lower row, 25 where they are subjected to drier air, which is less moisture-laden than the air at the top-row. The turning of the screens, in order to bring the vegetables to the next row below, as well as the turning back of 30 the screens in their normal position is performed for all screens of the same horizontal row simultaneously, as these are coupled by a suitable mechanism, which effects about a quarter of a turn of the screens.
- 35 The driers, as generally used at present, have flat screens, each of which can be turned about an axle, mounted in the center of the screen. This arrangement results however in the difficulty, that by turning 40 the screens of one row, the vegetables, when falling down upon the next row below, are not sufficiently spread, and on account of their wet condition, form a coherent mass. According to the small surface, 45 which the vegetables offer the air, the drying process is very slow. In order to avoid this disadvantage, valves are provided in the side walls of the drying chambers, for the purpose of giving access from outside 50 to the separate horizontal rows of screens. The vegetables after being brought to a lower row of screens, are equally spread over the whole surface of the layer by a suitable instrument, which is brought inside by

opening the corresponding valve in the side 55 wall. It is obvious, that this manipulation not only results in a great loss of heat or hot gases, but it also requires workmen, who at all times must be available for this purpose. 60

The present invention avoids these incompatibilities, and at the same time has the advantage of shortening the drying process. For this purpose the screens of all, or of several of the horizontal rows are formed 65 by two planes in about perpendicular position to each other, their section-line lying in the same line with the spindle, around which the screens are turned. The turning of these cross-screens always is effected 70 in the same direction and for one quarter of a turn. On each layer of cross-screens the vegetables are dried successively on the left and on the right part of each screen (or in an opposite way). 75

The advantage of this arrangement is, that the drying process, on each layer is more intensive, for the reason, that after the screens have been turned about a right angle, the vegetables are again subjected on 80 the same screen, to the drying action of the air. The current of heated air however, comes in contact with another surface of the vegetables, these being turned upside down. Consequently, the drying action on 85 each layer of screens being more intensive, it will be sufficient to arrange less layers of screens than are used in the existing driers, thus making it possible to build the new apparatus lower. The fact, that 90 less layers of screens will be sufficient for an effective drying action, results in another advantage viz., that the drying gases in their path through the apparatus, find less resistance, thus allowing to decrease the pressure at which they are introduced at the bottom of the drier. 95

According to the invention, the cross screens can only be turned in one direction, and this direction is for each following layer 100 opposite to that of the preceding one.

The invention is illustrated in the accompanying drawings as follows:

Figure 1 is a section through a double drying chamber to which the invention is 105 applied.

Fig. 2 is a front view of the drier shown in Fig. 1.

Fig. 3 is a view similar to Fig. 2, showing the mechanism for obtaining uni-directional movement of the screen shafts.

The double drying chamber, as shown 5 in the drawings, consists substantially in a frame 1, forming a case, the walls of which are covered with heat-insulating material X. The upper part of this frame forms a closed space, in which are arranged the drying-screens 2 and 6, reaching over the whole 10 with the drying chamber. The lower part opens into funnel-shaped tanks 3, each of which is closed at the bottom by a valve 4. In these tanks the dried vegetables are gathered, and discharged into suitable cases or 15 barrels, which are placed under the opening of the valve 4.

In the driers, as illustrated in the drawing, the screens are arranged in five horizontal 20 layers above each other, each layer having eight screens placed side by side, which screens are all pivotally mounted on the parallel axles 5. The uppermost and the lowest layers have flat screens 2, while 25 in the illustrated case, all intermediate rows are formed by cross-screens 6, of the above-mentioned shape. The transverse-section through these screens has the form of a cross. The position of the two upper rows 30 in relation with each other can be such that the vertical part of the cross-screens serves as stopping arrangement for the flat screens of the top-row when these are brought into vertical position. By striking 35 the flat screen against the cross-screen below, the vegetables lying on the flat screen, are shaken thus preventing sticking to the screen. All the screens of the same layer are suitably coupled, thus enabling 40 the workman to turn them all at the same time by operating one handle or crank 9.

The bottom of the drying chamber is connected through opening W and pipe Z to a blower Y through which heated air is 45 brought to the drier, passing successively through the different layers of drying screens, and leaving the drier at the top through a perforated plate 7.

By turning one of the cranks 9, the shafts 50 15 are driven by means of the bevel-gear-wheels 13 and 14, this motion being transmitted to the spindle 5 of the screens by means of the worms 16 and the worm-wheels 17. The direction in which the 55 cranks 9 can be turned is opposite for each successive layer. This may be obtained by means of a pawl and a ratchet wheel which permit the crank to turn in one direction only, see A, A¹, and B, B¹, of Fig. 3.

60 The top-row is turned by means of the wheel 10, which is moved by a chain or a rope 11, and the rod 18, which is connected to the spindles 5 by the levers 19. The length of the stroke, when turning the flat 65 screens of this layer, is limited by a slot

20 of the wheel 10, this slot coöperating with a pin 21, fastened to the rod 18. The flat screens at the bottom of the drier are in the same way operated by means of a lever 22 and the slot 23.

When the drier is in action, the vegetables are first placed on the screens 2 of the top-layer a, and exposed to the drying action of the heated air, and afterward brought successively to the layers b, c, d 75 and e. This is effected by turning the screens 2 of the layer a, when the wheel 10 has made about a quarter of a turn.

In the drier, shown in Fig. 1, the flat screens of the layer "a" are turned in a 80 direction opposite to that of the hands of a clock, when the vegetables are transmitted to the next layer. The vegetables then fall on the left side of the horizontal part of the cross-screen of the second layer, where 85 they are again subjected to the action of the drying gases. Meantime the screens of the top-layer are returned into their horizontal position, and filled with fresh vegetables.

When the vegetables are dried during a 90 certain time on the layer b, the cross-screens of this row are turned in the direction of the hands of a clock, making about a quarter of a turn. The vegetables are turned upside down and at the same time 95 are placed on the other side of the screen, to the right of the spindle, around which the screen is turned. Here again, the vegetables are dried, and other parts of the vegetables lying at the surface are subjected to 100 the drying action of the heated air. When the layer b again is turned, the vegetables fall upon the right side of the screens of the layer c, which every time make a 105 quarter of a turn in the direction, opposite to that of the hands of the clock. Consequently, on this layer the same operation takes place as on the layer b, with the only difference that the vegetables are first placed on the right hand side and afterward on 110 the left hand side of the screen. It is obvious that both sides of the cross-screens, the left as well as the right are simultaneously active; after the screen has been turned for a quarter of a turn the empty 115 side gets its material from the layer above. The flat screens 2 of the bottom-layer can only make a quarter of a turn, like the screens of the top layer, and are then returned into their original position.

120 What I claim is:

1. Improvements in driers for vegetables, with chambers, in which horizontal rows or layers of drying screens, pivotally mounted on parallel spindles, are placed above each other and of which the screens of the same layer are suitably coupled to be turned together, the screens of several of the horizontal rows being formed by two intersecting planes substantially perpendicular to 125

each other, their intersection lying in the same line with the spindle, around which the screens are turned.

2. A drier according to claim 1, characterized in that the cross-screens of each row only can be turned in one direction, and that this direction for each following layer is opposite to that of the preceding one.

3. Improvements in driers for vegetables, 10 with chambers, in which a number of horizontal rows or layers of drying screens, pivotally mounted on parallel spindles, are

placed above each other, and of which the screens of the same layer are suitably coupled to be turned together, the screens of all of 15 the horizontal rows being formed by two intersecting planes substantially perpendicular to each other, their point of intersection being in line with the axis of the spindle around which the screens are 20 turned.

In testimony whereof I have hereunto set my hand.

SALOMON VLESSING.
